UNITED STATES PATENT OFFICE.

JOHN E. GREENAWALT, OF NEW YORK, N. Y.

SINTERING APPARATUS.

Application filed March 21, 1923. Serial No. 626,667.

To all whom it may concern:

Be it known that I, JOHN E. GREENAWALT, a citizen of the United States, residing at New York, in the county of New

5 York and State of New York, have invented certain new and useful Improvements in Sintering Apparatus, of which the following is a specification.

10 My invention has relation to improvements in sintering apparatus of the intermittent type, and is directed more particularly to the igniting hood of the apparatus, being an improvement over that shown in my United States Patent No. 1,110,623, dated Sept. 15, 1914. In the patent just referred to the igniting hood, after being moved over the sintering pan, is bodily lowered to engage the top edge of the pan. In the present application the hood is provided 15 with a sealing frame which is lowered to seal the joint of the hood with the pan instead of lowering the entire hood. It is far more efficient and economical to move the sealing frame instead of the hood, since the 20 former weighs only a few hundred pounds against several tons for the hood in large installations. The present invention possesses other advantages which will be better apparent from a detailed description of the 25 invention in connection with the accompanying drawings, in which—

Figure 1 is a top plan of my improved igniting hood with the perimetrical sealing frame mounted on it, and in raised position; Fig. 2 is a side elevation of the hood with part of the same in section; Fig. 3 is an end elevation with a part of the hood shown in section; Fig. 4 is a plan view of half the hood frame with the sealing frame 30 mounted thereon; Fig. 5 is a side elevation of the parts shown in Fig. 4 showing the lowered position of the sealing frame in dotted outline; Fig. 6 is a cross-sectional detail on the line 6—6 of Fig. 4; Figures 35 7, 8, and 9 are cross-sectional details on the lines 7—7, 8—8, and 9—9 of Fig. 5 respectively; Fig. 10 is an enlarged side elevation and section combined, of the coupling means between the air supply main and the air 40 pipe on the hood.

45 Referring to the drawings, 1 represents the top edge of a sintering pan which is well known in the art, and which is described in detail in my patent No. 1,110,623 before referred to, and 2 represents the surface of 50 the material in the pan that is to be sintered.

It is essential that the surface of the material be ignited over its entire area, for which purpose an igniting hood H is provided, said hood being mounted on wheels 60 3 adapted to ride on tracks 4 disposed adjacent the sides of the pan (or pans). The hood is formed by side channel walls 5, 5, and end channel walls 6, 6 bolted together at the corners by bolts 7, and roof R, the assembly of side and end walls constituting the hood frame. The roof R of the hood is supported by a series of I-beams 9 extending from one side wall 5 to the other to which they are bolted, and the end roof plates 10, 65 extending across each end, are bolted directly to end I-beams 9 by bolts 11, there being spacing pieces 12 between the roof plates 10 and I-beams. The intermediate I-beams 9 carry roof supporting members 13 which are secured to the I-beams by bolts 14 and spacing pieces 15.

70 As will be seen in Fig. 2, the end roof plates 10 and the roof-supporting members 13 are shouldered to receive the flange of roof plates 16, 17, and 18, which rest on them. The roof plates 16 are provided with peep holes a, the roof plates 17 are imperforate, and roof plates 18, the burner plates, are provided with a central perforation o to receive the burner (to be described hereinafter) and a series of smaller perforations o, or air holes. Obviously, the roof plates have shoulder and flange connection 75 with their adjacent plates so as to make a practically air-tight connection. It is desirable that no air enter the hood during the ignition of the material in the pan, except through the air holes o in roof plates 18.

80 An oil burner 19 is disposed in the opening o of each roof plate 18, said burner being provided with a flange 20 near its upper end, said flange being bolted to angle iron supports 21 which are in turn secured to the adjacent roof-supporting I-beams 9. The cap 22 of the burner is connected 85 through suitable piping 23 to the air supply line 24 and is connected to the oil tank 25 by suitable piping 26. The oil is fed to the burner under a suitable pressure maintained in the oil tank, said pressure being supplied by the pipe 27 leading from an air tank 27'. The details of the burner 19 need not be here described as the burner is made the subject of a separate application filed here- 90 with Ser. No. 626,669. Suffice it to say, however, that the mixture of oil and air is 95 100 105 110

discharged from the periphery of the distributing cap 28 as a fine spray or circular sheet, and on igniting spreads a sheet of flame over the entire surface of the material 5 2 in the pan 1. The oil tank 25 is provided with an asbestos housing 29, and within the housing and in close proximity to the tank is a steam coil 30 for preheating the oil.

The piping 23 for conducting the air to 10 the burner 19 is connected by means of stuffing boxes 31, 31 to an oscillatable pipe section 32 having an arm 33 carrying counterweights 34 on the inner end, and an elbow 35 provided with a coupling flange 36 at 15 the end of a short piece of pipe 37 at the outer end. There is a similar coupling flange 38 at the outlet end of the air line 24, and when the flanges 36 and 38 are brought together they may be locked by means of the 20 latches 39, 39 pivotally connected between ears 40, 40, and 41, 41 of a ring 42 supported loosely on studs 43 secured in the lower flange 38 at diametrically opposite points. The ears 41, 41 are far enough apart to receive 25 the cam 44 of cam lever 45, the cam being bifurcated to receive one of the latches 39, and a pin 46 traverses slots *s* in the ears 41, 41 and holes in the cam and latch. Now, when the burners are to be supplied with 30 air for ignition, the coupling flanges 36 and 38 are brought together, the latches 39 are lifted up so as to bear on the flange 36, the cam lever raised to the position shown, whereupon the cam 44 forces its latch down- 35 ward and the lever ring 42 upward, the pin 46 moving down in the slots *s* and the cam bearing against the ring between the ears. The ring is provided with bosses 47 on diametrically opposite sides for engaging the 40 under side of the lower flange 38 and forcing it into intimate contact with the upper flange 38 which is being pulled down by the latches.

By referring to Fig. 2 it will be seen that 45 the bottom of the hood H is a little above the top of the pan 1 (about one inch clearance required in moving the hood from one pan to another) leaving a space that must be closed practically air-tight for the proper functioning of the hood. A sealing frame 50 F is provided for this purpose, said frame consisting of side members 50, 50 and end members 51, 51 (the side and end members each being made in two pieces) bolted together at the corners 52. The side members 55 5, 5 and end members 6, 6 of the hood are channel-shaped in cross-section with the upper wall of the channel longer than the lower, and the side members are each provided with a series of ribs 53, 54, 55, 56 ex- 60 tending between the walls of the channel, from each end to the middle, where the upper wall of the channel is widened to carry a bearing bracket 57. There are four 65 smaller brackets 58 about equally spaced along each member 5 and on a line inside of

the bracket 57. Bearing brackets 59 are positioned between the two pairs of brackets 58, for carrying the axles 60 of wheels 3 on which the hood H is carried. Ribs 55, 55 are L-shaped, there being a right-angle notch 70 *n* at the bottom and a flange *m* at the top of the ribs, the purpose of the notches *n* being to receive the sealing frame as we shall presently see. The end members 6, 6 of the hood frame are also provided with two 75 spaced L-shaped ribs 62, each having a right-angled notch *n'* at the bottom and a flange *m'* at the top. Guide members 63 and 64 are bolted to the flanges *m* and *m'*, said guide members extending downwardly to 80 opposite the bottom of the side members 5 and end members 6 respectively, the notches *n* and *n'* thus forming spaces between the side and end frame members and the guides. The object of these spaces is to receive the 85 side members 50 and end members 51 of the sealing frame F, said members being of right-angled cross-section and each having two pairs of ribs 65 so spaced along their length that when the sealing frame is assembled and disposed around the hood between the ribs 55 of the side members and guides 63, and ribs 62 of end members and guides 64, said pairs of ribs 65 will bear against 90 the respective guides. At the same time the 95 vertical legs of the sealing frame will bear against the faces *f* of ribs 55 and faces *f'* of ribs 62. The notches *n* and *n'* are deep enough to receive the full width of the sealing frame when it is raised, at which time 100 the bottom edge of the frame F is level with the bottom edge of the hood frame. The manner of supporting and moving the sealing frame is as follows:

A rock shaft 65' is mounted in the bearings 57, 57, and just inside each bearing is a double lever 66 to the ends of which are connected links 67, 67, said links also being connected to the long arms of bell-crank levers 68, 68 pivotally connected to 110 brackets 58. There are also bell-crank levers 69 mounted on the end brackets 58, and the long arms of these levers are connected by links 70, 70 to the long arms of levers 68, 68. Thus it will be seen that by rocking 115 the rock shaft 65' in the proper direction by a lever 71 keyed on one end of the shaft, all the bell-crank levers 68, 69 on both sides of the hood frame will be rocked so as to depress their horizontal arms, to the ends 120 of which are connected links 72 which pass through slots *x* in the hood side members 5, 5 and are connected on their lower ends by eye-bolts 73 to the side members 50, 50 of the sealing frame F. And, obviously, the 125 depressing of the horizontal arms of the bell-crank levers permits the sealing frame F to descend until it rests squarely on the upper edge 1 of the sintering pan, sealing the same against the admission of air be- 130

tween the hood and the pan. In order that the sealing frame may be easily raised it is counter-balanced by weights 74 secured to the outer ends of two counter-weight levers 75, 75 keyed to the rock shaft 65 just inside the levers 66, 66, and a latch 76 is pivoted to an I-beam 9 opposite the lever 71, said latch being adapted to engage the upper edge of the lever when it is lowered, thus preventing the sealing frame F from accidentally descending.

The operation of the apparatus may be briefly described as follows:

Assuming that in Fig. 2 the material in the pan 1 has already been ignited, and the sealing frame F raised. The hood H is then wheeled to the next pan, and when squarely over the pan the lever 71 is released from the latch 76 and the sealing frame F permitted to descend onto the upper edge of the pan 1. The valves controlling the oil and air supply to the burner 19 are then opened and on igniting the inflammable spray from the distributing cap 28, immediately the hood is filled with a sheet of flame which ignites the charge of material in the pan evenly over its entire surface. After the material is thoroughly ignited the valves are closed, extinguishing the flame, (except for a small pilot light if desired) after which the lever 71 is rocked downwardly thus raising the sealing frame through the link and bellcrank connections, and the sealing frame held in its raised position by the engagement of the lever by the latch 76. The hood may now be wheeled to the next pan, and so on.

Features shown but not described are well known in the art, or already shown and described in my patent aforesaid, except the burner which is made the subject of a separate application as heretofore mentioned. The invention is also susceptible to modification in the hands of a skilled mechanic, and I do not wish to be understood as restricting the same to the precise features shown and described. In fact, so far as I am aware, an igniting hood of the character described provided with a sealing frame is basically new.

Having described my invention, I claim:

1. In an apparatus of the character described, the combination with a support for the material to be treated, of a hood adapted to be disposed over and spaced from said support, and means mounted on the hood for sealing the space between the hood and support against the influx of atmospheric air currents and means for moving the sealing means into and out of engagement with the support.

2. In combination with a vessel holding a charge to be treated, a hood adapted to be

supported over the charge in spaced relation with said vessel, means carried by the hood for sealing the space between the hood and the vessel, and means for removing said sealing means from the vessel while the hood is supported over the charge.

3. In combination with a vessel holding a charge to be treated, a hood adapted to be placed over the charge in spaced relation with the vessel, a sealing frame disposed around the margins of said hood and in contact therewith, guides on the hood for the sealing frame, and means for moving said frame into and out of contact with the vessel.

4. In combination with a vessel holding a charge to be treated, a hood adapted to be placed over the charge in spaced relation with the vessel, a sealing frame disposed around the margins of the hood and in contact therewith, supporting members for the sealing frame carried by the hood, and means for raising and lowering said supporting members simultaneously.

5. In combination with a vessel holding a charge to be treated, a hood adapted to be placed over the charge in spaced relation with the vessel, a sealing frame disposed around the margins of said hood in contact therewith and in contact with the vessel, guides on the hood for the sealing frame, a rock shaft mounted on the hood, suitable connections between the sealing frame and the rock shaft whereby the sealing frame may be raised on rotating said shaft in a given direction, and a counterbalance mounted on the shaft for the sealing frame.

6. In combination with a vessel holding a charge to be treated, a hood adapted to be placed over the charge in spaced relation with the vessel, said hood comprising a rectangular frame and a roof supported thereby, guide members secured to the side and end frame members in spaced relation therewith, a rectangular sealing frame disposed around the hood frame and confined between the respective members of said frame and the guides, a rock shaft mounted on the hood frame, a plurality of link and lever connections between said rock shaft and sealing frame for suspending said frame in place, a counter-balance mounted on the shaft for the sealing frame, a lever fixed on the rock shaft whereby the same may be rotated to raise the sealing frame, and means for holding the sealing frame in raised position, said sealing frame being adapted to move downwardly in contact with the vessel on releasing the holding means.

In testimony whereof I hereunto affix my signature.

JOHN E. GREENAWALT.
